JOURNAL BOX ARRANGEMENT

Walter H. Baselt, Flossmoor, Ill., assignor to
 American Steel Foundries, Chicago, Ill., a corporation of New Jersey

Application December 7, 1946, Serial No. 714,708

26 Claims. (Cl. 308—47)

1

My invention relates to journal boxes for use on railway cars and has particular reference to means for protecting the journal box lugs against wear.

In the present day railway car trucks, the journal box is generally formed as an integral part of the side frame. On the top wall of the box is provided an integral cam-faced lug to which is hinged a lid or journal box cover, said lid carrying resiliently actuated means slidably engaging the said cam faces by means of which the lid is held either in closed position or in open or elevated position, as is common in journal box lids. These means, on opening and closing the lid, eventually wear away not only the cam faces against which they bear, but also the opening in the lug through which passes the pin or pintle affording a pivotal connection for the lid. Any looseness in this connection permits the lid, upon movement of the car, to flap and vibrate, consequently accelerating the wear of the engaging parts.

Refacing or building up worn cam faces is an expensive operation and if the journal opening in the lug is also worn, refacing the cam faces alone will not entirely eliminate any looseness in the assembly. Replacement of the lug is impractical since it involves not only the cost of removal of the worn lug, by cutting it off the box, but also the arduous task of properly positioning and welding on the new lug.

I have devised means to overcome these difficulties, and it is the object of my invention to provide inexpensive, easily replaceable wearing means on the journal box lugs.

My invention contemplates providing on the journal box lugs readily replaceable wear means comprising a cam face sheathing portion and bushing portions, the sheathing portion being sleeved over the cam faces of the lug and the bushing portions fitting into the journal opening in the said lug.

These and other objects of my invention will be apparent from the specification and drawings, wherein:

Figure 1 is a fragmentary top plan view of a journal box embodying one form of my invention with one of the parts of the novel wear means being shown in pre-assembly position;

Figure 2 is an elevation of the assembly shown in Figure 1 with the parts in final assembled position, the left half being a front elevation thereof, and the right half being a rear elevation thereof with a portion of the journal box being shown in section, as indicated by line 2—2 of Figure 3;

2

Figure 3 is a fragmentary sectional view of the assembly taken in the transverse vertical plane substantially as indicated by line 3—3 of Figure 2;

5 Figure 4 is a top plan view similar to that shown in Figure 1 and embodying a modification of my invention;

10 Figure 5 is a view in elevation of the assembly shown in Figure 4, the left half of Figure 5 being a front elevation, and the right half a rear elevation, partly in section, taken in the plane indicated by line 5—5 of Figure 6;

15 Figure 6 is a sectional view taken in the transverse vertical plane substantially as indicated by line 6—6 of Figure 5; and

20 Figure 7 is a sectional view similar to that of Figure 6 and showing another modification of my invention.

Describing my invention in detail and referring first to Figure 1—3, the journal box (fragmentarily shown) generally indicated 2, comprises a top wall 4 on the top of which adjacent the outboard edge thereof is formed the integral lug, generally designated 6, said lug comprising the integral inwardly flaring spaced parallel legs or pedestals or bracket ribs 8, 8 at opposite ends thereof, said ribs including hub portions 10 (Figure 2) between which extends the integral member or body 12 of the lug formed with cam faces 14 and 16 (Figure 3) at the front and top thereof, said member also having a rear face 18 and being necked down or recessed as at 17, at the bottom where it joins the said journal box top wall 4 in the usual manner and presenting the converging under surfaces 20 and 22. An opening 24 is provided in the lug 6, said opening extending transversely of said ribs through the hub portions thereof and longitudinally through the said member 12, the opening 24 being adapted to receive a pin or pintle means (not shown) journaled in the lid (not shown) in the usual manner.

45 A wear member 26 is sleeved over the lug 6, the wear member 26 having at opposite ends thereof the downwardly bent flat annular disc or flange elements 28, 28 fitted against the remote sides of the said hub portions 10, and each of these elements has a central opening 30 aligned with the said opening 24 in the lug 6.

50 Integrally joined to these elements with portions of the outer peripheries thereof are the cup-like structures 32, 32 complementary in form to the hub portions 10 and capping the same, in a manner as best seen in Figure 2, said structures merging into the integral intermediate wear plate or sleeve or sheathing portion 34 con-

toured to the said member 12 and having the angularly related webs 36, 38 and 40 corresponding in angularity to that of said faces 14, 16 and 18 (Figure 3) respectively and tightly pressed thereagainst and encompassing the same.

It will be appreciated from a consideration of Figures 1-3 that the webs 36 and 38 of the member 34 thus provide the cam surfaces 42 and 44 against which an associated member (not shown) may bear in the usual manner for holding the lid on which it is usually mounted in normal open or closed position.

To secure the sleeve 34 to the member 12, the lower edges of the webs 36 and 40 are curled under the said under surfaces 20 and 22 of the member 12 as at 46 and 48 respectively, as illustrated in Figure 3.

Within the opposite ends of the opening 24 are positioned bushings 50 which may be provided with annular plates or flanges 52, 52 of the end caps, each bushing passing through the opening 30 in the adjacent element 28 and thus additionally securing the wear member 26 to the lug 12. The flanges 52 are each held in assembled position on the lug 12 and interlocked therewith by the integral arms 56 projecting from one side of each annular plate 52, said arms passing behind the adjacent bracket rib 8 and being bent against the inner surface thereof as at 57, as shown in Figure 3.

In assembling the device shown in Figure 1, the preformed wear member 26 is sleeved over the lug so that the cuplike structures 32, 32 of the said member fit snugly on the hubs 10, 10 of the lug and at the same time the webs 36, 38 and 40 fit snugly on the faces 14, 16 and 18 respectively.

Thereafter, the portions 46 and 48 of the webs 36 and 40 are bent inwardly into the respective recesses 17, 17 of the lug until they bear against the respective surfaces 20 and 22.

The bushed portions 50 of the end caps are then inserted through the openings 30 in the disc elements 28 in the wear member 26 and extend into the opposite ends of the complementary opening 24 in the lug at which time the flanges 52 of each of the end caps bear against the outer face of the adjacent disc elements 28. The arm 56 of each end cap is then bent around the adjacent rib 8 so that it snugly engages the inner surface of the said rib 8.

Referring now to Figures 4-6 illustrating another form of my invention, it will be observed that the construction of the lug 100 is unchanged from that described in connection with the previous modification, said lug 100 being mounted on the top web 102 of the journal box, generally indicated 104, and having the inwardly flaring bracket ribs or legs 106 at opposite ends thereof with the hub portions 108 between which extends the integral member 110 having the usual cam faces 112 and 114 at the front and top thereof, and the rear face 116 (Figure 6). The lug is necked down or recessed as at 117 at the bottom thereof providing the under surfaces 118 and 120.

Within the lug 100 is provided the opening 122 serving the same purposes as the opening 24 described in connection with the previous modification.

On the opposite ends of the lug are positioned the wear members generally designated 124, 124, each of said members comprising an annular disc or flange portion 126 having a central opening 128 which may be formed by extruding the bushing 130 from said disc, said bushing 130 fitting into the adjacent end of the said lug opening 122. 75

Each disc portion 126 rests against a side 132 of the adjacent hub portion 108.

An arm 133 extends from the edge of each disc portion 126 and passes behind the adjacent rib 106, said arm carrying an integral wear plate or sleeve or sheathing member 134 preferably projecting at right angles therefrom and contoured to the faces of said lug by being bent thereover in such manner that it closely adheres to said faces. It will be observed in considering Figure 5 that the sleeve or sheathing members 134, 134 of the wear members 124, 124 are arranged in tandem and substantially cover the lug faces from end to end and provide the cam surfaces 136 and 138 upon which may ride in the usual manner the resiliently actuated member (not shown) carried by the journal box lid (not shown).

To more adequately secure the sleeve member 134 to the lug 100 the bottom edge of the web portion 140 (Figure 6) of the sleeve member 134 is bent as at 142 under the adjacent under surface 110 of the lug.

In assembling the device shown in Figure 4, each bushing 130 is fitted into one end of the opening 122 with the associated flange 126 bearing against the outer surface 132 of the hub 108. The arm 133 is then bent so that the offset or recess 135 therein snugly engages the inner surface of the hub 108 to afford an interlock therewith. Thereafter, the member 134 is bent from the position shown in dot and dash lines in Figure 6 to the position shown in solid lines therein so as to snugly confine and interlock with the portion 110 of the journal box lug. One of the wear elements 124 is shown in preassembly position at the top of Figure 4 and the other wear element is shown in final assembled relationship with the journal box lug.

Figure 7 illustrates another modification of my invention, and it may be noted that the construction of the lug 150 is the same as that in the previous modifications.

The wear member 152 is identical with that shown in Figures 4-6 with the exception that the offset portion of the arm 154, which passes behind the adjacent rib 156 of the lug, has an inturned bottom edge 158 extending into the recess 160 of the lug and clamping the adjacent portion of the lug for thus securing the wear member on the lug and especially securing the portion 162 thereof sheathing the cam faces 164 and 166 and the rear face 168 of the said lug.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. A journal box having an integral lug with cam faces thereon, a member sleeved over said lug and having end portions bent around the respective ends of said lug and having an intermediate portion removably interlocked with said lug and sheathing said cam faces, bushing elements extending through openings in said end portions into a longitudinal opening in said lug, and means on said elements for interlocking the same with said lug.

2. Wear means for a journal box lug, comprising a malleable sleeve element having a top web and spaced side webs depending therefrom, said top web being arranged at an acute angle with respect to one of said side webs and at an

obtuse angle with respect to the other of said side webs, said side webs having inwardly bent portions at their lower edges, a hollow cap portion at each end of said element integral with the adjacent ends of said webs, and a bushing member at each end of said element having a cylindrical portion extending longitudinally of said element through an opening in the adjacent cap portion, a flange at one end of said cylindrical portion for abutment with the external side of the related cap portion, and a malleable arm on said flange adapted to be bent around an associated lug for interlocking engagement therewith.

3. A journal box having an integral cam-faced lug with a pintle opening therethrough, a jacket on said lug covering the cam faces thereon and having disclike members abutting the opposite ends of said lug, bushing elements in the opposite ends of said opening and projecting through respective members for interlocking said jacket with said lug, and means on said bushing elements clamping portions of said lug for interlocking engagement therewith.

4. A wear element for a journal box lug, comprising a bushing portion with a flange at one end, a bendable fastening arm on the flange at one side of said bushing portion, and a bendable sheathing strip on said arm spaced from said flange and extending transversely of said bushing portion.

5. In a journal box, a lug thereon and having external cam faces and a pin opening therethrough, a wear element jacketing said lug and having a portion contoured to said faces and sheathing the same and having other portions abutting the ends of said lug, and means for interlocking said element with said lug comprising bushing means in said opening interlocked with said other portions of said element.

6. In a journal box, a lug thereon having cam faces and a pin opening therethrough, detachable wear means on said lug comprising a member sheathing said cam faces and having end portions in abutment with respective ends of said lug, bushing means in said opening and interlocked with said portions, and fastening means on said bushing means hooked to said lug for preventing axial movement of said bushing means within said opening.

7. In a journal box, an integral lug thereon having cam faces and a pin opening therethrough, and wear means for said lug comprising a pair of elements detachably interlocked with the lug, each element comprising integral bushing and wear plate portions disposed respectively in said opening and on said cam faces.

8. In a journal box, the combination of an integral cam-faced lug thereon, wear means on said lug comprising a member sleeved on said lug, bushing elements projecting into an opening in said lug from the opposite ends thereof and interlocked with said member, and means on said bushing elements clamping portions of said lug, and interlocking said elements and member with said lug.

9. In a journal box, a lug with a pin opening therethrough, cam faces on said lug, wear means for said lug detachably mounted thereon and comprising a pair of similar elements arranged side by side longitudinally of said lug, each element including a bushing portion extending into the adjacent end of said opening, an arm portion connected to the bushing portion and wrapped around a part of said lug, and a wear

plate portion connected to said arm and superposed onto said faces in clasping engagement with said lug.

10. A journal box wear element blank comprising a cylindrical bushing portion, a flange around said bushing portion, an arm on said flange extending radially of said bushing portion, and a coplanar strip on said arm extending longitudinally transaxially of said bushing.

11. In a device of the class described, a journal box lug with a pin opening therethrough and comprising a body portion with cam faces thereon, and detachable wear means interlocked with said lug comprising a sheathing covering said body portion and contoured to the faces thereon, and bushings connected to said sheathing and projecting into opposite ends of said opening.

12. In a journal box, a lug thereon having a pintle opening therethrough and comprising shoulder portions at its ends and an intermediate body portion with cam faces thereon, removable lining means for protecting said faces and said opening against wear, comprising sheathing means and bushing means, said sheathing means embracing said body portion and covering said faces, said bushing means extending into said opening and interlocking said sheathing means with the lug, and means for holding said bushing means against endwise movement in said opening interlocked with said shoulder portions and connected to respective bushing means.

13. In a journal box, in combination, an integral lug thereon having cam faces and a pintle opening, and wear means detachably interlocked with said lug and comprising bushing and sheathing portions extending into said opening and jacketing said faces respectively said bushing portion interlocking said sheathing portions with the lug.

14. In a journal box, a lug having a section with cam faces thereon, a wear member at each end of said lug, each member having a portion wrapped around said section sheathing said faces, and a bushing portion extending into the adjacent end of a pin opening through said lug.

15. A wear element for a journal box lug comprising spaced front and rear webs and an interconnecting diagonal top web arranged at an acute angle with respect to said front web, cam faces on said front and top webs, the lower edges of said front and rear webs being bent toward each other for gripping the underside of an associated journal box lug.

16. In a journal box, the combination of an integral cam-faced lug thereon, detachable wear means interlocked with said lug and comprising a jacket sheathing said cam faces, and bushings extending into a pin opening in said lug from the opposite ends thereof connected to the jacket for interlocking the jacket with the lug.

17. A journal box lug having an intermediate portion with cam faces, enlarged end portions and a pintle opening therethrough, the combination of wear means for said lug comprising sections wrapped around said intermediate portion and removably interlocked therewith and covering said faces and comprising other sections arranged to interlock said first-mentioned sections with the lug and extending into the opening to provide bushing means therefor and interlocked with said end portions.

18. In an arrangement for protecting a journal box lug having cam faces intermediate its ends and a pintle opening therethrough, means having

a portion covering said faces and removably interlocked therewith and having another portion connected to the first portion and extending into said opening to interlock said first portion with said lug and affording a bushing for the opening.

19. In an arrangement for protecting a journal box lug, wear means comprising a sheath having a portion covering said lug and having another portion holding said first portion on the lug and extending into a pindle opening in said lug to provide a bushing therefor.

20. A protective covering for cam faces and pindle opening of a journal box lug comprising sheathing means wrapped around the lug and covering said faces and extending into said opening to provide bushing means therefor and interlock the segments thereof covering said faces with said lug.

21. In a covering for cam faces of a journal box lug recessed at its lower edges, a wear member wrapped around said lug on said faces and having at least one of its lower edges bent into a recess in the lug to fasten said member on the lug.

22. In combination with a journal box lug having an enlarged upper portion with cam faces on the top and front sides thereof, a protective covering for the lug comprising a member wrapped around said lug to conform to said faces, and means detachably interlocking said member with the lug comprising at least one lower edge of said member bent under said enlarged portion.

23. Wear means for a cam-faced journal box lug comprising a one-piece wear member having a cylindrical bushing and a deformable piece connected to the bushing for bending around the lug to cover cam faces on the lug.

24. Wear means for a journal box lug having

10
15

5 a pin opening and cam faces comprising a member having a portion at one end formed as a bushing for insertion into said opening and having another portion connected to the first-mentioned portion and adapted to be wrapped around said lug to cover said faces, said portions being formed and arranged to interlock each other with the lug to prevent accidental disassembly thereof from the lug.

10 25. A wear member for a journal box lug comprising a blank with a bushing at one end and an arm extending from the bushing and having two angularly related bendable portions for wrapping around the lug.

15 26. A covering for a cam-faced journal box lug with an enlarged end portions comprising a member with an intermediate portion having angularly related sections conforming to the cam faces on the lug and having caps at the ends of the intermediate portion adapted to fit over said end portions.
